DRINKING CUP

Thomas H. Eyles, Leominster, Mass., assignor to Foster Grant Co., Inc., Leominster, Mass., a corporation of Delaware

Filed Oct. 10, 1963, Ser. No. 76,930

Term of patent 14 years

(Cl. D44—9)

FIG. 1 is a top perspective view of a drinking cup showing my new design.

FIG. 2 is a plan view of the drinking cup.

FIG. 3 is a bottom view of the drinking cup.

FIG. 4 is a cross-sectional view thereof taken on lines 4—4 of FIG. 1, partially shown in phantom for convenience of illustration.

The characteristic features of my design reside in a drinking cup having an outside portion comprising vertically, extending equally spaced flutes having substantially flat outer surfaces joined by V-shaped grooves all as shown.

I claim:

The ornamental design for a drinking cup, substantially as shown and described.
